UNITED STATES PATENT OFFICE.

WENZEL ANTON RADOUŠ, OF PRAGUE, AUSTRIA-HUNGARY.

HAND EMBROIDERING-MACHINE.

1,076,909.

Specification of Letters Patent. Patented Oct. 28, 1913.

Application filed February 18, 1911. Serial No. 609,438.

To all whom it may concern:

Be it known that I, WENZEL ANTON RADOUŠ, engineer, residing at Graben 12, Prague, in the Kingdom of Bohemia, Empire of Austria-Hungary, have invented a new and useful Hand Embroidering-Machine, of which the following is a specification.

My invention relates to improvements in 10 the well known hand embroidering-machines used for embroidery-work, made by forming the design of a continuous series of loops on one side of the fabric.

The objects of my improvements are, first, 15 to execute the work in a more exact, easy and quick manner, second, to avoid the inconveniences found in the usual form of embroidering machine now in use.

I attain these objects by the mechanism 20 illustrated in the accompanying drawing, in which—

Figure 1 is a front elevation, Fig. 2 a side elevation of a machine embodying my invention, Fig. 3 a cross section on the line 25 3—3, Fig. 2, Fig. 4 a cross section on the line 4—4, Fig. 2, and Fig. 5 a cross section on the line 5—5, Fig. 2.

Similar letters refer to similar parts in the several views.

Referring to the drawing, *p* is the guide rod inserted in the handle *t* and having the usual presser foot, at its lower end. On the rod *p* slides a guide shoe *g*, in which the needle-support *z* is rotatably mounted on 35 the pivot *y*. The needle *a* is secured in the needle-support by means of a screw *u*. The guide-shoe *g*, together with the needle *a*, are moved up and down by means of a reciprocating rod *f*. Said rod carries a foot *e* 40 which bears either against a guard formed of lugs *d*, *d'* on the upper end of the guide-shoe *g* when the guide shoe is being pulled up or against the lateral walls *n*, *n'* of the guide-shoe *g* when the guide shoe is being 45 forced down. The length of the stroke of the needle *a* is limited in the downward direction by a stop *m* striking against the handle *t*. The position of the stop *m* on the rod *f* can be adjusted. The stop has two 50 legs which are each provided with a hole *m'* through which passes the rod *f*. A spring *k* forces the wall of one or the other hole *m'* into one of the notches *l* provided on the rod *f*. Thus the length of the stroke of the 55 rod *f* and the needle *a*, and therefore also the length of the loops, may be regulated.

With this arrangement the maximum stroke is not limited to the distance between the first and last notches, but to that distance plus the length of the stop *m*, because the 60 bow may be moved to a position where the lower hole engages with the upper notch, or it may be moved down so that the upper hole engages with the lowermost notch, thus providing for a wide range of adjustment. 65 A greater refinement of adjustment may be attained by so locating the notches that only one hole in the bow will engage with a notch, the other hole engaging with the rod between two notches illustrated. This 70 adjustment may then be equal to half the distance between notches.

In using the machine the head *v* on the rod *f* is held with one hand and the handle *t* with the other hand, the presser foot being 75 in contact with the fabric at all times. By moving the head *v* up and down, the needle *a* is passed through the fabric and is drawn back. The rod *f* is provided with an eye *o*, through which passes the embroidering- 80 thread *r* coming from a suitable source of supply such as the usual coil and passing through the eye of the needle. When the eye of the needle passes through and below the fabric and draws the loop of thread *r* 85 with it, the thread is free to pass through the eye *o*. When the head *v* is moved upward the thread *r* becomes pinched between the lugs *d*, *d'* and the foot *e* of the ascending rod *f*, thus forming the loops. By this 90 arrangement the length of thread between the eye *o* and the eye of the needle is unchanged, so that the delivered length of thread is always the same for the formation of the loops; these latter are therefore of 95 uniform length.

In hand embroidering machines, as hitherto known, the length of the stitches depends on the stroke of the connecting rod, because the oscillations of the needle-support *z* 100 are limited by a fixed lug. Therefore the stitches are long or short as the loops are made long or short by the adjustment of the machine. For the purpose of producing different lengths of stitches irrespective of 105 the lengths of the loops the needle-support is provided according to the present invention with an adjustable lug. The latter consists of a screw *b* screwed in the needle-support *z* and maintained in the desired position by means of a nut *c*. By screwing in the screw *b* to the full extent the needle *a* 110

will be adjusted so as to assume a vertical position, so that the needle makes the holes in a single place only in the fabric and any number of loops may be formed at the said place. As the screw *b* is screwed outwardly the needle *a* with the needle-support will be also tilted, and the length of the stitches will be increased. The extent of inclination of the needle support will determine the length of the stitches. The needle-support is combined with a spring *w*, engaging with the end of the needle-guard below its pivot *y*, and tending to engage the support with the screw. This spring will be compressed as the needle is pushed into the fabric, thus allowing the needle to assume the vertical position at the end of its down stroke; at the end of its up stroke, after the point of the needle leaves the fabric, the needle will be tilted to the angle determined by the position of the screw, this action being caused by the spring.

I am aware that prior to my invention

hand embroidering machines have been made with vertically reciprocating needles forming loops below the cloth, I therefore do not claim such a machine broadly; but

I claim:

A hand embroidering machine having a needle support, a needle, an operating handle, a reciprocating rod sliding in the handle, and means for determining the extent of movement of the needle, such means comprising an adjustable stop, said stop having two legs, a perforation in each leg through which the rod passes, said rod having a series of notches, there being a spring for engaging a leg of the stop with a notch on the rod.

In testimony whereof I have signed my name to this specification in the presence of two subscribing witnesses.

WENZEL ANTON RADOUS.
